UNITED STATES PATENT OFFICE

HELEN L. OTTENHEIMER, OF CHICAGO, ILLINOIS

DEVICE FOR HOLDING BABY IN BED

Application filed December 8, 1930, Serial No. 500,715. Renewed March 25, 1932.

My invention relates to an improved device for holding a child in its bed. It relates to a device which not only keeps the child from climbing out of its bed but also prevents the child climbing around and kicking around in such a way as to remove its covers during the sleeping period.

The principal object of this invention is the provision of an improved device of this character.

Another object is the provision of a device of this character which is simple, inexpensive and convenient to use.

Another object is the provision of a device of this character which will interfere to a limited extent with the movement of the child while in bed.

Other objects and features of the invention will be apparent from a consideration of the following detailed description taken with the accompanying drawings, wherein

Fig. 1 is a fragmentary perspective view showing the device as attached to the child's bed when in use, and

Fig. 2 is an enlarged plan view of the device.

In general the device comprises means for forming a connection to the bottom of the child's nightdress, means adapted to be attached to the child's bed on the foot thereof and a connecting member between the two fastening means. A swivel support is provided between the members so that the child can turn freely without entangling itself in the device or in its own nightdress. The connecting member is in the form preferably of a slender strip, as will be apparent from a consideration of the embodiment shown in the drawings.

Means for forming a connection to the child's nightdress 10, is shown in the form of an ordinary garter clasp, having the two co-operating members 11 and 12 between which the bottom of the nightdress is engaged. However, any form of fastener may be used, such as a safety pin for example. The clasp is attached to a swivel frame 13, in which is pivoted and supported the end ball 14 of the chain 16. The chain as shown is a swivel ball type chain, although other types of chain

may be employed and the clasp and tape secured to its ends preferably by a suitable swivel connection.

At the opposite end of the chain, a swivel member 17 is provided for receiving the ball 18 at the opposite end of the chain, and means attachable to the bed in the form of a strip of tape 19 is secured to the swivel member 17. The tape is secured to the swivel member 17 intermediate its ends, and this permits the two ends to be used for the purpose of attachment to the child's bed 19 in a suitable manner. The particular place of attachment to the bed is immaterial, although for older children it may be desirable to attach the tape at a point out of reach of the child. Preferably, the tape is attached to the springs or some underneath portion of the bed in such a way as to interfere as little as possible with the tucking of the coverlet in at the foot of the bed. Also it does not interfere with the making of the bed. The drawings illustrate the preferred manner of attachment.

I have found that this device can be secured in place very readily to hold the child in bed, or as quickly released from engagement with the child's nightdress, or from engagement with the bed itself if the child is to be removed from bed. Preferably, the clasp is secured to the lower end of the garment so as to prevent the child from putting its feet out but at the same time permitting the child to draw its legs up. Also, it is preferably secured at the center of the bottom edge so that there is an even pull on the shoulders of the child if it attempts to crawl toward the head of the bed. While allowing considerable freedom of movement of the child, it will hold the nightgown down but at the same time will not hamper the child greatly, except to prevent the child from crawling upwardly and over the sides or foot of the bed, as it will often do to get out from under its coverlet. Its movements otherwise are not restricted. The swivels provided on the device permit the child to turn in any direction and its nightdress can turn with it, but the child will still be prevented from

crawling upwardly as it naturally will do in attempting to arise.

Although any suitable connection between the tape and clasp may be provided, such as a narrow strip of cloth or the like, I have found that the swivel ball type of chain is very well suited for the purpose, because the entire chain swivels and the end balls of the chain are readily usable as part of a swivel connection. As the drawings show, a narrow slot 17—a is provided in the swivel member so that the chain may be readily removed, or if by any chance the end ball is broken off from the chain, a connection can be made to the swivel member readily by means of another of the chain balls.

The drawings show the device attached to a dress type of nightdress. The device may be used with pajama type garments with equal satisfaction. Sometimes it may be found desirable to use two of the devices with pajamas, attaching one clasp to each leg or foot of the garment.

Although I have described my invention in detail so that those skilled in the art will understand the same, it is obvious that I am not restricted to the particular form and the invention is limited only by the scope of the appended claims.

What I claim as new and desire to protect by Letters Patent of the United States is:

1. In a device for holding a child in bed, a clasp adapted to engage the bottom of a child's nightdress, a tape adapted to be tied to the child's bed near the foot thereof, and a swivel connection between the tape and clasp.

2. In a device for holding a child in bed, a clasp adapted to engage the bottom of a child's nightdress, a swivel ball chain having one end attached to the clasp, and means for securing the other end near the foot of the bed.

3. In a device for holding a child in bed, a clasp adapted to engage the bottom of a child's nightdress, a swivel ball chain having one end attached to the clasp, and a tape intermediate the ends of which is attached the other end of the chain, said tape adapted to be fastened to the child's bed near the foot thereof.

4. In a device for holding a child in bed, a clasp adapted to engage the bottom of a child's nightdress, a swivel ball chain having one end attached to the clasp, and a tape intermediate the ends of which is attached the other end of the chain, said tape adapted to be fastened to the child's bed near the foot thereof, swivel joints being provided between the chain and clasp and between the chain and tape.

5. In a device for holding a child in bed, a clasp adapted to be secured to the bottom of a child's nightdress, a tape adapted to be secured to the child's bed, a slender connecting

strip, a pivotal connection between one end of the strip and the clasp, and a pivotal connection between the strip and tape.

6. In a device for holding a child in bed, a clasp adapted to be attached to the bottom of a child's nightdress, a swivel member secured to the clasp, a tape adapted to be tied to the child's bed near the foot thereof, a swivel member secured to the tape intermediate the ends thereof, and a swivel ball chain, each end ball of which is loosely held in the swivel members.

7. In a device for holding a child in bed, a garter clasp adapted to be attached to the bottom of the child's night-dress, a swivel ball chain, a swivel connection between the clasp and one end of the chain, a tape adapted to be tied to the bed near the foot thereof, and a swivel connection between the opposite end of the chain and said tape, said connection being intermediate the ends of the tape, whereby the ends may be used for tying.

In witness whereof, I hereunto subscribe my name this thirteenth day of November, 1930.

HELEN L. OTTENHEIMER.
